CLAIM

The ornamental design for a rear bumper for electric vehicle, as shown and described.

DESCRIPTION

FIG. 1 is a top, front, and right side perspective view of the new design for a rear bumper for electric vehicle, showing an illustration of use on the bottom of an electric vehicle; FIG. 2 is another top, front, and right side perspective view thereof, with the exemplary electric vehicle removed for clarity of details;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines shown in the drawings illustrate environment and portions of the rear bumper for electric vehicle that form no part of the claimed design.

The shading lines shown in the drawings represent the approximate three-dimensional contour of the design, and are not intended to indicate surface decoration.
